UNITED STATES PATENT OFFICE.

GEORGE BENNS, OF CHICAGO, ILLINOIS, ASSIGNOR OF ONE-HALF TO JOHN J. MITCHELL, OF NEW YORK, N. Y.

FLAT-IRON HEATER.

SPECIFICATION forming part of Letters Patent No. 335,421, dated February 2, 1886.

Application filed April 18, 1885. Serial No. 162,634. (No model.)

To all whom it may concern:

Be it known that I, GEORGE BENNS, of Chicago, in the county of Cook and State of Illinois, have invented certain new and useful 5 Improvements in Flat-Iron Heaters, of which the following is a specification.

This invention has reference to an improved flat-iron heater which can also be used advantageously as a heating-stove for warming 10 the shop or other place in which the heater is used.

In the accompanying drawings, Figure 1 represents a side elevation of my improved flat-iron-heating stove; Fig. 2, a vertical central section; Fig. 3, a horizontal section on line xx , Fig. 1; Fig. 4, a plan of the same; and Figs. 5, 6, and 7 are respectively a bottom view, a side view, and an end elevation of the top stays that connect the top of the 20 fire-pot with the jacket. Fig. 8 is an enlarged detail view of the mechanism for clamping the retaining-guides to the inner face of the filling-strips.

Similar letters of reference indicate corresponding parts.

Referring to the drawings, A represents the fire-pot of my improved flat-iron-heating stove, which fire-pot is made of hexagonal or other polygonal shape, according to the number of flat-irons to be heated. The fire-pot A is supported on the rim of a basket, B, which is provided with a horizontally-oscillating grate-section, C, that is centrally pivoted to a diametrical supporting-bar, b, and oscillated by a shaker-rod, b², as shown clearly 35 in Fig. 3. The rim of the basket B rests on a ring-shaped bottom, D, which is attached by a downwardly-extending flange, d, to the cylindrical wall of the ash-pit E. To an exterior flange, d', of the ring-shaped bottom D is attached a cylindrical jacket, F, that is formed of as many sections as there are sides of the fire-pot, which sections are separated by slots f', and connected to the fire-pot by 40 radial partitions f and by inclined top stays, g. The radial partitions f extend from the center of the jacket-sections to the corners of the fire-pot, and form, with the same, compartments for the flat-irons to be heated. The partitions 45 f are riveted to lugs of the ring-shaped bottom and retained by recessed side lugs, g', of

the top stays, g. The vertical slots f' between the jacket-sections are of such a width that the handles of the flat-irons can freely pass through the same to the outside, as shown in 55 Fig. 2.

The upper part of the flat-iron-heating compartments is closed by an axially-movable top ring, F', the inner circumference of which rests on anti-friction balls of a retaining-collar, F², of angular cross-section, while the outer circumference is bent downward and incloses the upper edge of the jacket F. The top ring, F', is preferably provided with half as many openings as there are compartments, 60 which openings are closed by hinged doors or gates F³, that are readily opened or closed by suitable handles, h, for conveniently removing the flat-irons from or replacing them into the heating-compartments. The handles 70 h serve also for shifting the top ring, F', from one compartment to the other until the motion is arrested by downwardly-extending stop-pins, h', which are arranged near each door F³, and which abut against the radial 75 partitions f, as shown in Figs. 2 and 4.

The ring-shaped bottom D is provided with a raised convex portion, d², inside of the flange d, said convex portion serving to support the flat-irons either in a position close to the walls 80 of the fire-pot when they are to be heated or in an outwardly-inclined position, as shown in dotted lines in Fig. 2, when they are not required for use. The annular space of the bottom D, outside of the wall of the ash-pit, 85 is provided with perforations e, through which air may be drawn into the heating-compartments, said openings being opened or closed by means of a movable ring, e', having openings registering with the openings of the 90 bottom D. The perforated ring e' is provided with a handle, e², that extends to the outside of the jacket F and serves for moving the ring e', so as to admit air to the interior of the compartments or shut off the same. The 95 air thus drawn into the compartments is heated up and emitted through the slots of the jacket and through the openings of the top ring, F', when the flat-irons are removed or replaced. The flat-iron heater serves by this 100 arrangement also as a heating-stove, by which the room in which the same is used is effect-

- ively heated at a considerable saving of fuel. When the heater is not required for heating flat-irons—as, for instance, on Sundays—the vertical slots between the sections of the jacket 5 F are closed by ornamental filling-strips F⁴, which are shown in detail in Fig. 2^a, which filling-strips are inserted from the top after opening the doors F³ and retained by locking-plates i i, as shown in Figs. 2 and 3.
- 10 From the inner face of each of the filling-strips F⁴, near the upper end thereof, projects a lug, i', having an ear, i'', at its inner end, provided with a transverse perforation or eye. A locking-plate, i, fits over the ear i'', and is 15 clamped against the shoulder i³ on said lug by means of a wedge, i⁴, which is inserted in said eye in the ear and driven in, all as clearly shown in Fig. 8. Near the lower end of said strips an L-shaped piece, i⁵, projects therefrom and extends to one side. When the 20 hinged cover is raised, and the filling-piece F⁴ inserted from the top, the locking-plate i extends across said slot and holds the strip F⁴ in place, while the L-shaped piece i⁵ at the bottom assists.

The reliable connection of the jacket F with the fire-pot A is accomplished by the top stays, g, which are riveted by lugs at their outer ends to the jacket F and anchored by 25 laterally-extending lugs g² at their inner ends to downwardly-extending lugs g³ of the angular collar F², as shown clearly in Fig. 5, in such a manner that each lug g² may move vertically between the lugs g³ on each side thereof. The 30 lugs g² at the inner ends of the stays g support, in connection with the downwardly-extending lugs g⁴ of the collar F², the upper end of the fire-pot A in such a manner as to permit the vertical expansion of the fire-pot A 35 by the heat without interrupting or straining its connection with the jacket F, but preventing the lateral displacement or disarrangement of parts. The angular collar F² is provided at its upper side with a circumferential groove for the 40 anti-friction balls of the top ring, F', as shown in Fig. 6. On the upper rim of the collar F² rests a dome-shaped cover, G, that closes the top of the fire-pot. The cover G is provided with an opening and a sliding door, G', that 45 moves sidewise by means of a slide-ring, G², fitted to the upper contracted part of the cover G.

For supplying the fuel to the upper part of the fire the door G' is moved sidewise, and 50 the fuel dumped through the opening into the magazine M at the interior of the fire-pot. On the rim at the upper part of the cover G rests an intermediate detachable pipe-section, m, that forms the connection with the stove-pipe. 55 The rim of the cover G, as well as the pipe-section m, is recessed at diametrically-opposite points, said recesses registering with each other, so as to form the bearings for the pivots of the damper m'. By detaching the intermediate pipe-section, m, the damper can be 60 removed for cleaning, also the cover G, so

that access is given to the interior of the fire-pot.

The sides of the polygonal fire-pot are reinforced by inwardly-extending diamond-shaped projections, which have the advantage not only to contract the throat of the fire-pot, so as to confine the gases, but also to strengthen the same against warping and cracking. This feature of the fire-pot and the movable venti- 70 lating-ring of the bottom form part of a separate application for Letters Patent for a heating-stove, which has been filed at the same date herewith—viz., April 18, 1885, Serial No. 162,633—and to which reference is made. 75

Having thus described my invention, I claim as new and desire to secure by Letters Patent—

1. The combination of a polygonal fire-pot, a ring-shaped bottom surrounding said fire-pot and having a raised convex ring therein, 80 an exterior cylindrical jacket having vertical slots, and a movable top ring having openings with hinged doors, substantially as described.

2. The combination of a polygonal fire-pot, 85 a cylindrical jacket surrounding the same and having vertical slots for the handles of flat-irons, a ring-shaped bottom for said jacket, a top ring having openings with hinged doors, an angular collar resting on the top of the fire- 90 pot and having downwardly-extending lugs, and top stays rigidly attached to said jacket and having lugs embracing said downwardly-extending lugs, whereby vertical expansion of the fire-pot is permitted, substantially as de- 95 scribed. 100

3. The combination of a fire-pot, an exterior jacket formed of sections separated by vertical slots, a ring-shaped bottom for said jacket, a movable top ring having openings with hinged 105 doors, and detachable filling-strips for closing said slots, substantially as described.

4. The combination of a fire-pot, an angular collar resting thereon, said collar having downwardly-extending lugs, an exterior jacket, 110 radial partitions, and top stays within said jacket provided with side and end lugs, said stays being secured to the jacket at one end, their side lugs supporting said partitions, and the lugs at their other ends engaging said 115 downwardly-extending lugs of the collar, substantially as described.

5. The combination of a fire-pot, an exterior jacket having vertical slots, radial partitions within said jacket, a ring-shaped bottom for 120 said jacket, a movable top ring having openings with hinged doors, and downwardly-extending stop-pins for limiting the motion of the top ring in either direction, substantially as described. 125

6. The combination of a fire-pot, an exterior jacket formed of sections separated by vertical slots, a ring-shaped bottom for said jacket, a movable top ring having openings with hinged doors, detachable filling-strips for closing said 130 slots, and fastening devices for said filling-strips, substantially as described.

7. The fire-pot A, exterior jacket, F, formed of sections separated by vertical slots, the ring-shaped bottom D for said jacket, and movable top ring, F', provided with hinged doors, in combination with the strips F⁴, provided with the lug i', having shoulder i³ and perforated ear i², the locking-plate i, and the wedge i⁴, for clamping said locking-plate against said shoulder, as and for the purpose specified. 15
5
10. 8. The fire-pot A, exterior jacket, F, formed of sections separated by vertical slots, the ring-shaped bottom D for said jacket, and movable top ring, F', provided with hinged doors, in combination with the strips F⁴, provided near its lower end with an L-shaped piece, i⁵, and 20 near its upper end with the lug i', having the shoulder i³ and perforated ear i², the locking-plate i, and the wedge i⁴, for clamping said locking-plate against said shoulder, as and for the purpose specified.

In testimony that I claim the foregoing as my invention I have signed my name in presence of two subscribing witnesses.

GEORGE BENNS.
